UNITED STATES PATENT OFFICE

LAWRENCE E. GOELLER, OF CIRCLEVILLE, OHIO

DESIGN FOR A BROOM SOCKET

Application filed January 6, 1931. Serial No. 38,211. Term of patent 7 years.

To all whom it may concern:

Be it known that I, LAWRENCE E. GOELLER, a citizen of the United States, residing at Circleville, in the county of Pickaway and State of Ohio, have invented a new, original, and ornamental Design for Broom Sockets, as shown in the accompanying drawings and described in the following specification.

This invention relates to a new and ornamental design for broom sockets in which: Figure 1 is a side elevation; and Figure 2 is an end elevation.

I claim:

The ornamental design for a broom socket as shown.

LAWRENCE E. GOELLER.
